UNITED STATES PATENT OFFICE.

IGNATZ GOLDBERGER, OF CLEVELAND, OHIO.

UNDERGARMENT.

SPECIFICATION forming part of Letters Patent No. 606,203, dated June 28, 1898.

Application filed April 8, 1897. Serial No. 631,243. (No model.)

To all whom it may concern:

Be it known that I, IGNATZ GOLDBERGER, a citizen of the United States, and a resident of the city of Cleveland, in the county of Cuyahoga and State of Ohio, have invented certain new and useful Improvements in Undergarments, of which the following is a specification.

My invention relates more particularly to a low-necked sleeveless shirt or vest and combination or union suit for women and children; and its object is to improve the garment, whereby it will avoid the necessity of having sleeves or any other pieces of cloth attached to the sides of the body portion for the purpose of covering the armpits and under the arms for protection against perspiration, and also to improve the fit at the neck and shoulders and to render it an easy and comfortably fitting garment, especially at the armholes, so that the same may fit and be used for any size of arm regardless of the size of the body portion.

Another object of my invention is to improve the body portion in such a way that there will have to be no scallops or notches cut out or slits cut into the sides to form armholes, yet the garment is to be of such a construction as to be provided with armholes, and the parts that form them will also act as shoulder-straps and as a dress-protector for perspiration, thus doing away with the use of dress-shields; also, by constructing the armholes in the manner that I shall describe it will avoid the necessity of having jointed parts at or under the armpit of the body portion, which generally form heavy seams that annoy the wearer. In carrying out this part of my invention I employ a tubular body portion of knitted ribbed fabric, and at the upper end on each side I construct a peculiar shaped armhole, and the parts which form them are also adapted for shoulder-straps and armpit-coverings. The upper portion of the armholes thus formed projecting in an upward direction and beyond the body portion form the shoulder-straps, the ribs of which run in a horizontal direction or transversely with the ribs of the body portion and the elasticity of which yields in a vertical direction. The lower portions of the formed armholes, which parts extend beyond the shoulder-straps in a

lateral direction, provide armpit-coverings and occupy more or less of an upright position, with the ribs running longitudinally with reference to the length of the body and the elasticity of which yields in a horizontal direction with the body. The parts which provide the armholes and which are adapted to be used the same as shoulder-straps and armpit-coverings are continuous parts from the top of the body portion and are of a double layer of cloth, which, owing to the construction, have unbroken folded edges on the outer side ends of the body for the purpose of receiving an elasticity in both horizontal and vertical directions. The inner sides of the formed shoulder-straps and upper body portion which provide the neck and body opening are finished with some device for the purpose of adjusting a tape or ribbon to be used as drawing-strings to fasten the shoulder-straps to the body of the wearer to keep the garment from falling off the shoulders. When a garment of this description is slipped over the body of the wearer and the shoulder-straps are properly fastened by means of the tape around the neck, the lower portions forming the armpit-coverings, owing to the shape and construction of the armholes and through the elasticity of the cloth yielding in both directions, will not fall away from the body, but will hug close to the under sides of the arms, covering the armpits, and will yield with every movement of the arms with the greatest ease and comfort, and thereby act as an absorber of perspiration.

Another advantage arises from my construction of the armholes, so that they will fit any size of arm and will cause no tightness, binding, or any other inconvenience at or under the armpits to hurt the wearer; will also save material and labor and will lessen the cost of manufacture over other constructed garments that were made heretofore for similar use, and will therefore be a more desirable article in general.

My invention relates, further, to the drop-flap or seat-opening closure of a combination or union suit, which I provide with a band attached to the upper edge thereof. The ribs of this band run in a horizontal direction, so that its elasticity yields only vertically. When the band is attached to the back of the

body, it will render the garment yielding to such an extent that it will not draw at the shoulders and will not pull or tear the buttons off the body, which is caused by the strain 5 when stooping or bending down. Garments heretofore constructed with drop-flaps for the seat-opening on such suits and pantaloons have the upper portion of seat-opening closure or drop-flap finished with a non-elastic band or with an elastic band that will only 10 yield in a horizontal direction. A drop-flap with a band unyielding vertically always causes the garment to draw at the shoulders of the wearer and in every such case will tear 15 or pull the buttons off when stooping down, for the reason that the body portion has the ribs running vertically and therefore being practically inelastic in that direction which by stooping necessitates the enlargement of 20 the body portion in a longitudinal direction. My improved drop-flap does away with all these defects and will therefore furnish a more desirable garment, especially when used by children, to which they are mainly adapted. 25 In order that my invention may be fully understood, I will proceed to describe it with reference to the accompanying drawings, in which—

Figure I is a view of a piece of cloth or 30 knitted fabric of tubular body folded flat, showing the front or back cut out at the upper portion, so as to form armholes, shoulder-straps, and armpit-coverings when folded inward to the inside of the body. - Fig. II is a 35 view of the upper portion of the body where the cut portions are folded over inward to the inside of the body on a horizontal line to form a double layer of cloth for the armhole portions and shoulder-straps. Fig. III is a 40 view of the upper portion of the body, showing the shoulder-straps raised to their proper position. Fig. IV is a full view of the upper body portion, as shown in Fig. III, with a lace edging and tape adjusted, showing it in its 45 complete condition. Fig. V is a perspective view of a shoulder portion of the same. Fig. VI is a view showing a modification of the tubular body and the front or back of the upper portion to form a double layer of cloth for 50 the armpit-coverings before they are folded over to the inside of the body and before the separate shoulder-straps are attached to the vertical inner edges. Fig. VII is a view of 55 the front or back of the upper body portion having two shoulder-straps attached to the vertical inner edges on both sides, front, and back body portion before they are folded into the inside of the body portion to form armpit-coverings and shoulder-straps. Fig. VIII is 60 a view of the front or back of the upper body portion folded over to the inside of the body portion on a horizontal line to form double thicknesses for the armpit-coverings and shoulder-straps before the shoulder-straps 65 are raised to their proper position. Fig. IX is a view of the front of the upper body portion having the shoulder-straps raised to their

right position and finished with an edging and tape to form the neck-opening. Fig. X is a view of one of the shoulder-straps before being folded. Fig. XI is a perspective of a folded shoulder-strap. Fig. XII is a back view of a low-necked sleeveless combination or union suit having a drop-flap seat-opening closure attached and fastened. Fig. XIII 75 is a back view of the same, showing the drop-flap unfastened. Fig. XIV is a view of the band of single layer before being folded over. Fig. XV is a view of the band folded and ready for attachment. 80

For the body portion of the garment shown in Figs. I to V, I employ a piece of knitted cloth 1, preferably made of ribbed fabric and of tubular body of any construction. The piece of tubular cloth is folded flat, and at 85 the end which is used for the upper portion the cloth is cut on both layers from the top of both side edges 2, as shown in Fig. I, from points *a* in downward diagonal lines 3 to the points *b* of the inner body portion, and thence 90 from the points *b* in a straight horizontal upper line 4 across the body to the point *c* at the center of the body portion, thence from the point *c* in a vertical line 5 to the point *d*, thence from the point *d* in straight horizontal 95 lower lines 6 toward the outer sides of the body portion and ending at points *e*, so as to bring the same in a parallel line with the upper line 4. The upper side portions 7 thus formed are each of a V shape on each side 100 edge of the body portion. These side portions are folded over to the inside of the body portion at the dotted line 8 in Fig. I, which brings the horizontal lines 4 and 6 together, and the portions embraced by these lines form 105 the shoulder-straps 9. The cut edges from 110 *a* to *b* are attached to the inner sides of the body, and the edges from *c* to *d* of the rear and front parts forming the shoulder-straps or upper portion of armholes are sewed together or otherwise attached to each other, as shown in Fig. III, and are raised up side- 115 wise toward the outer side of the body to bring the two shoulder-straps in a more or less upright position and the ribs approximately 120 horizontal or transverse of the ribs of the body portion, thereby bringing the elasticity to yield in a vertical direction. By folding the cloth over to the inside of the body portion at the dotted line 8 I provide an unbroken 125 edge 10 thereat, which, when the shoulder-straps 9 are raised to their proper position, and owing to the open cut edges from *b* to *c* and *d* to *e* on the edges of the neck-opening, the cloth of the shoulder-straps will yield to 130 the full extent or capacity of the ribs, which in use causes the ribs of the outer folded edges to close up tight and form a curved or segmental shaped armhole 11, with the outer upper portion slightly slanting in an outer 135 downward direction. The lower parts of the folded edges, which extend beyond the shoulder-straps to the outer side edges of the body portion on the line 10 in a horizontal direc-

tion, form the armpit-coverings, which are continuous parts of the shoulder and body portions and occupy a more or less upright position, the ribs of which extend longitudinally and the elasticity of which yields horizontally, as in Fig. III. The inner parts of the shoulder-straps and body portion which form the neck and body-opening of the garment are finished with an edging 12 or some other border for the purpose of passing a string or tape 13 through the same. The tape may be used for drawing the neck-opening together to keep the garment from falling or slipping off the shoulders, as shown in Fig. IV, and which when adjusted to the body of the wearer will bring the shoulder-straps inward closer to the neck, thereby drawing the folded side edges of the body or lower armhole portions closer to the armpits and under the arms. Owing to the fact that the armhole portions occupy an upright position they will not fall away from the body, but will hug close under the arms, and while the outer edges of the armholes are of a double layer of cloth and the folded edges being unbroken by and free from any slits the elasticity will yield approximately in opposite directions, which will permit the armholes to yield and contract with every movement of the arms, thereby forming an unlimited space between the shoulders and armpits, which will therefore fit any sized arm and be made an easy and comfortable garment to wear in general; also, the parts that cover the armpits will act to absorb the perspiration, thereby protecting the dress of the wearer, which will not necessitate the using of dress-shields. The minor details of construction, as shown, may be varied without departing from my invention.

For the modified construction of my invention I employ two separate shoulder-straps 9^a, preferably made of knitted ribbed fabric, which are each of a single layer of cloth, as shown in Fig. X, and folded over on the line 5^a to form a double layer, as shown in Fig. VII, and which when attached to the body portion have the folded unbroken edges at the center of the shoulder-straps and the ribs extending horizontally or transversely with the body portion and are attached by their vertical edges to the inner edges of the body portion. The body portion in this construction has two V-shaped side portions 6, one at each side edge of the body portion, as shown in Fig. I, and each is folded inward with the strip portion on the line 8^a, and then the side portions are attached by stitching to the inside of the body portion. The inner side edge of the shoulder-straps 9^a and the upper inner body portion are finished in the same manner as in my first construction. In this modified construction (shown in Figs. VI to XI) I form two seams at each side of the front and back body portion where the shoulder-straps 9^a join the body, as shown in Fig. VII, and therefore do not form any seam at the center of shoulders. The edges 14 of the

shoulder-straps are attached to the vertical edges 15 of the body portion, one at each side front and back, thereby omitting any seam at the center of shoulder-straps. The dotted line 5^a in Fig. X shows the fold for the unslotted edges forming the center of shoulder-straps. In my first construction I provide only one seam for each shoulder-strap, which is located at the center of shoulder, whereas in this construction I provide two seams for each shoulder-strap, which are located one each at the front and back body portion where the straps join the body.

The body portion for this garment may be of any desired construction and be knit on any suitable knitting-machine and the tubular body portion may be with or without seams.

For the construction of the upper band 20 of the drop-flap 21 I use a piece of cloth, preferably made of knitted ribbed fabric, as shown in Fig. XIV, which is folded over at the line 22 to form a double layer of cloth, as shown at Fig. XV. The piece of double cloth thus formed has the ribs running in a horizontal direction and the elasticity of which will yield in a vertical direction only and is attached to the edges of the formed drop-flap, as shown in Figs. XII and XIII, and when attached will have the ribs or wales running crosswise with the ribs of the body portion and drop-flap, thereby producing an elasticity in a longitudinal direction with respect to the garment. The drop-flap in this construction is adapted to fold in a downward direction when opening the seat-closure, and when closed will fold in an upward direction and is attached to the back of body at the waist-line by means of buttons 23 and buttonholes 23^a or other suitable detachable connections, as shown in Figs. XII and XIII.

The strip 24 for the upper end of drop-flap may be of any construction, size, and shape, double or single, as desired. The strip is sewed or otherwise attached to the upper edge of the drop-flap, the ribs of the latter extending in a horizontal direction or crosswise with the ribs of the body portion, as stated.

The minor details of the construction may be varied without departing from the spirit of my invention.

Having thus described my invention, the following is what I claim as new therein and desire to secure by Letters Patent:

1. A garment comprising a tubular body portion cut at its central upper portion on longitudinal and transverse lines, said cut portions being turned outwardly and finished to form shoulder portions; substantially as described.

2. A garment constructed from a tubular blank of suitable material, the plies of the upper portion of which are cut on a dividing longitudinal line, and on a transverse line at the inner end of the longitudinal line toward the sides, the cut portions being doubled and the free portions turned outwardly producing

- shoulder-straps and armholes between the shoulder-straps and the sides of the garment, and the whole being finished; substantially as described.
5. 3. A garment constructed from a tubular blank of suitable material, the plies of the upper portion of which are cut away on lines converging inwardly from the sides to a transverse line and also on said transverse line; the plies being also cut on a dividing longitudinal line and on a transverse line at the inner end of the longitudinal line toward the sides, the upper portions being doubled and the free portions turned outwardly, producing shoulder-straps and armholes between the shoulder-straps and the sides of the garment, and the whole being finished; substantially as described.
4. An undergarment comprising a tubular body portion the central portion of the plies of the upper portion of which are severed on longitudinal and transverse lines and turned outwardly and finished to produce shoulder-straps and armholes between the shoulder-straps and the sides of the garment; substantially as described.
5. A garment comprising a flat tubular
- body portion formed with diagonal cuts providing side portions, with central horizontal cuts, and with a vertical cut providing central portions partly separated from the body portion, the side portions with about one-half the width of the separated pieces being turned over on a horizontal line inside of the body portion and the side portions stitched thereto to provide double thicknesses at the armpits, and the central pieces having their free ends stitched together, and turned outwardly to provide upwardly-projecting shoulder-straps, neck-opening and armholes, and the whole finished in suitable manner; substantially as described.
6. A garment comprising a seat-flap of ribbed fabric having the lower portion formed of a band in which the ribbing extends lengthwise of the garment, and the upper portion formed of a band folded over on a transverse line and in which the ribbing extends transversely of the garment so as to provide a yielding closure; substantially as described.
